Frank R. Sunderlin

Attorney

UNITED STATES PATENT OFFICE.

FRANK RANSOME SUNDERLIN, OF TERRE HAUTE, INDIANA, ASSIGNOR TO CENTRAL ADVERTISING SPECIALTY COMPANY, OF TERRE HAUTE, INDIANA, A CORPORATION OF INDIANA.

THERMOMETER TUBE.

Application filed August 9, 1923, Serial No. 656,600. Renewed December 9, 1926.

My said invention relates to thermometer tubes of an improved type, to a method of making such tubes, and to a machine for carrying out said method. It is an object of the invention to provide thermometer tubes which shall occupy less space than those now in use and which shall be so shaped that they may be more closely packed in shipping.

10 A further object of the invention is to provide thermometer tubes which shall be less easily broken than those now in use, particularly in shipping them.

Referring to the accompanying drawings which are made a part hereof and on which similar reference characters indicate similar parts,

Figure 1 is a perspective of the machine by which the method of my invention is carried out,

Figure 2, a front elevation of a thermometer tube made according to my invention, and

Figure 3, a side elevation thereof.

25 In the drawings reference character 10 indicates the lower member of a clamp or press and 11 the upper member, these clamps being hinged together at 12 and the lower member being rigidly supported in any desirable manner and preferably in horizontal position. A spring 13 is interposed between the clamps and holds them normally apart as indicated in the drawing. A rod 14 is attached to the upper clamp member and 30 at its lower end is secured to a foot pedal in any desirable manner thus providing means whereby the clamps may be drawn together by foot power and normally spread apart by the spring 13.

40 At the upper side of the upper clamp there is a caliper 15 having open jaws. This caliper provides means for calibrating the bulb of the thermometer as the tube is blown, the position of the tube being preferably as indicated in dotted lines at 16.

45 In the practice of my invention a tube is blown in the position indicated in dotted lines, the caliper serving to determine the correct diameter of the bulb. After the 50 correct diameter has been reached and while

the tube is still hot it is inserted between the free ends or jaws of the clamp and the pedal is depressed whereupon the upper clamp approaches the lower and flattens the bulb between the jaws of the clamp. It 55 will be understood that the caliper need not necessarily be located in the clamp since all that is necessary is that a clamp be so located in regard to the workman that he can insert the bulb between its jaws while 60 the glass is still hot so as to flatten the bulb.

The thermometer made according to my invention is shown in Figures 2 and 3. This thermometer has the usual stem 17 with a 65 longitudinal cavity for the reception of a body of mercury or other heat responsive liquid indicated at 18. At the lower end is a bulb 19 which as clearly shown in Figure 3 is flattened and ordinarily will 70 also be indented at 20 in the process of flattening although the indenting is not necessary. The hollow interior of the bulb as usual is connected to the longitudinal cavity in the tube.

75 The means constituting my invention may be modified in various ways which will be obvious to those skilled in the art and therefore I do not limit myself to what is shown in the drawings and described in the specification, but only as indicated in the appended claim.

Having thus fully described my said invention, what I claim as new and desire to secure by Letters Patent, is:

80 An apparatus for manufacturing thermometer tubes comprising a clamp having a relatively broad flat fixed jaw, a relatively broad flat movable jaw hingedly supported by said fixed jaw, spring means for holding the movable jaw in normally spaced relation from the fixed jaw, and manually operable means for moving the movable jaw toward the fixed jaw, substantially as set forth.

85 In witness whereof, I have hereunto set my hand at Terre Haute, Indiana, this 6th day of August, A. D. nineteen hundred and twenty-three.

FRANK RANSOME SUNDERLIN.
